WITNESS:

ATTORNEY

UNITED STATES PATENT OFFICE.

EGBERT VAN EERDE, OF NEW YORK, N. Y.

DUPLICATOR.

Application filed March 7, 1927. Serial No. 173,540.

This invention relates to the art of producing manifold copies by transferring the matter to be copied from an ordinary sheet of paper to the surface of a plastic or semi-plastic material, for example, a thin layer of clay of the character commonly known as "modeling clay".

A container of some character must be provided to hold the clay in such manner as to keep the transfer surface smooth and level, as well as to prevent too rapid drying. Experiments have shown that a container made of wood will buckle and warp and affect the transfer surface, and will in addition, rapidly absorb the moisture from the clay, so that the latter will quickly dry and break away from the bottom and sides of the container. A container of metal will quickly rust and corrode and the clay will rapidly dry out and lose its shape, so that the transfer surface will be ruined.

The present invention overcomes the above and other disadvantages by forming the bottom of the clay container of slate, this material being free from the disadvantages above mentioned.

The invention further provides a container arranged to form a guide or gage, whereby the transfer surface of the clay may be accurately renewed with a minimum amount of loss of time, labor and material.

With the above and other objects in view, the invention further includes the following novel features and details of construction, to be hereinafter more fully described, illustrated in the accompanying drawings and pointed out in the appended claim.

In the drawings:

Figure 1 is a plan view of the invention with the cover removed.

Figure 2 is a longitudinal sectional view.

Figure 3 is a plan view with the cover in place and partly broken away.

Referring to the drawings in detail where-in like characters of reference denote corresponding parts, the reference character 10 indicates a holder or container which may be of any suitable construction that includes a slate bottom 11 and a frame 12. For the purpose of illustration, this slate bottom may be set into the frame as shown at 13 and the latter may be formed of wood and extend only a slight distance upward. A shal-

low tray is thus provided to receive a thin layer of clay indicated at 14. The upper 55 face of this clay forms the transfer surface from which a number of duplicates of an original may be made. The clay is preferably of the character commonly known as "modeling clay" and its surface is preferably covered with a thin layer of glycerine. The glycerine is absorbed by the clay and keeps the latter in a plastic or semi-plastic condition and provides a thin transfer film upon the transfer surface mentioned. By 65 means of the container shown and described, the moisture is retained within the clay for a relatively long period and the clay is thus kept in proper condition for use during such period.

By the use of a wet sponge the matter being duplicated can be removed from the transfer surface so that the invention may be frequently used with very little attention.

Each time the matter being duplicated is removed from the transfer surface, a minute layer of clay is removed from this surface and eventually the transfer surface will become slightly rough and gritty. This surface may be renewed by spreading over it a 80 small amount of fresh clay reduced to a plastic condition by the addition of glycerine. An ordinary knife or spatula may be used for this purpose and by reason of the character of the frame 12, a gage or guide 85 will be provided for engagement by the knife when leveling the fresh or renewed transfer surface.

The invention is susceptible of various changes in its form, proportions and minor 90 details of construction and the right is herein reserved to make such changes as properly fall within the scope of the appended claim.

Having described the invention what is claimed is:—

A duplicator comprising in combination a slate including a rectangular frame having a single centrally located groove about the inner edge thereof, and a slate fitted in said grooves, and a pad reposing upon the slate and having its outer surface flush with the adjacent surface of the frame to provide a transfer surface.

In testimony whereof I affix my signature.

EGBERT VAN EERDE.
